Primary Examiner — Richard E Chilcot(74) *Attorney, Agent, or Firm* — Perkins Coie LLP(57) **CLAIM**

I claim the ornamental design for a rounded top electronic candle, as shown and described.

DESCRIPTION

FIG. 1 is a top perspective view of the rounded top electronic candle;

FIG. 2 is a side view of the rounded top electronic candle;
FIG. 3 shows a top view of the rounded top electronic candle; and,

FIG. 4 shows a cross section view of the rounded top electronic candle along the line 4-4 in FIG. 3.

The portions of the rounded top electronic candle shown in broken lines form no part of the claimed design.

1 Claim, 3 Drawing Sheets(56)
